William A. Walther, Dalton, Wis.

Application April 29, 1936, Serial No. 77,066

5 Claims. (Cl. 273—102.1)

This invention relates to improvements in targets and more especially to a novel self-indicating indoor or outdoor target.

The primary purpose of the invention is to provide a self-indicating target including cooperating mechanical elements adapted to be actuated by the force of bullets to indicate the accuracy of the shot as well as the point where the bullet hit on a particular part of any ring 10 of the target.

Another object is to supply a self-indicating target in which the parts are so constructed and arranged as not to bind in action.

A still further object is to furnish a self-indicating target in which the impacts of the bullets will be cushioned to prevent breakage of the parts.

A further object is to provide the front wall of such a target with means for catching lead and wild shots for safety purposes.

Another object is to supply a target of this type having cooperating mechanical elements which may be readily assembled or dismantled.

With the foregoing objects outlined and with other objects in view which will appear as the description proceeds, the invention consists in the novel features hereinafter described in detail, illustrated in the accompanying drawings, and more particularly pointed out in the appended claims.

30 In the drawings:

Fig. 1 is a front elevation of my improved target.

Fig. 2 is a vertical sectional view of the same partly in elevation, the section being taken on the line 2—2 of Fig. 1.

Fig. 3 is a transverse sectional view taken on the line 3—3 of Fig. 2.

Fig. 4 is another transverse sectional view taken on line 4—4 of Fig. 2.

Fig. 5 is a sectional view of a detail taken on the line 5—5 of Fig. 2.

Fig. 6 is a transverse sectional view of certain details taken on the line 6—6 of Fig. 2.

Fig. 7 is a horizontal sectional view of these details.

Figs. 8, 9, 10 and 11 are front elevations respectively of levers or jacks employed to operate indicating flags of the mechanism.

Fig. 12 is an elevation of a pawl employed for temporarily holding any of said flags in indicating position.

Fig. 13 is a plan view of a lever used for holding the pawl normally in inactive position.

Referring to the drawings, 1 designates the bull's-eye section of the target which is carried

by an axially movable, centrally disposed, horizontal guide rod 2. The ring sections 3, 4, 5 and 6 of the target are of successively larger diameters and arranged rearwardly of the section 1, and each ring is carried by four horizontal guide rods arranged in cross formation and numbered respectively 3a, 4a, 5a and 6a. The last-mentioned guide rods are connected to the ring sections by universal joints 7 to allow each ring element or section to tilt or incline when struck by a bullet.

All of the guide rods pass through holes 8a in the front wall 8 of the housing 9, and this wall is preferably made of steel in order to protect the mechanism arranged at its rear.

The guide rods are provided respectively with annular flanges, elements, or abutments 2b, 3b, 4b, 5b and 6b, and the holes in the front wall are sufficiently large to enable these flanges to pass through when the rods are inserted from the front thereof.

The rods are guided at their front end portions by an assembly 10 made up of four angular elements 11 (Fig. 5) provided with specially shaped notches 12. When the elements 11 are in assembled relation they form rearwardly flared apertures 13 (Fig. 2) to guide the rods and to allow slight wobbling movement of all the rods except the rod 2 to accommodate the tilting of the rings. The angular members 11 are secured in place by a clamping frame 14 which is held in position on the front wall of the casing by any suitable means such as screws 15. The clamping member carries a forwardly extending tube 16 which surrounds the rod 2. The rings 3 to 6 inclusive have a larger inside diameter than the outside diameter of the tube 16 to permit tilting of the rings.

A funnel-shaped lead catcher 17 flaring rearwardly, surrounds the target sections and a cylindrical ring 18 surrounds the lead catcher and projects forwardly from the casing. It functions as a wild shot catcher 19.

For the purpose of indicating whether the bull's-eye 1 or a particular ring is struck, the flanges 2b to 6b inclusive of the rods cooperate respectively with levers or jacks 2c, 3c, 4c, 5c and 6c, which are shown in detail in Figs. 6, 8, 9, 10 and 11. These levers are mounted respectively on horizontal pivot pins 2d, 3d, 4d, 5d and 6d, arranged respectively at successively lower elevations so that the levers will not interfere with one another in operation. The pivot pins are supported by an internal frame 21 and the levers are provided (Figs. 3 and 7) respectively

with forwardly and laterally extending arms **2e**, **3e**, **4e**, **5e** and **6e** which respectively actuate vertical push rods **2f**, **3f**, **4f**, **5f** and **6f**. These rods are arranged in a vertical plane extending longitudinally of the target and they are guided (Fig. 3) by upper and lower brackets **22** and **23**, each rod being provided with one or more abutments **24** designed to engage one of the brackets to prevent the push rod from rising too high.

10 In the detail view (Fig. 11) of the lever **2c**, it will be noted that it has an aperture **2k** to accommodate the rod **2**, and a slot **2m** to accommodate the four lowermost guide rods of the series. The lever **3c** (Fig. 10) arranged behind the lever **2c**, has an aperture **3k** to accommodate the guide rod **2**; apertures **3m** to accommodate the guide rods **3a**; and a vertical slot **3n** to form a passageway for the three lowermost guide rods of the series. Lever **4c** (Fig. 9) has an aperture **4k** forming a passageway for the rods **2** and **3a**, and it also has four apertures **4m** to accommodate the guide rods **4a**. A slot **4n** permits the two lowermost guide rods **5a** and **5b** to pass through this lever. Lever **5c** (Fig. 8) has a large aperture **5k** to accommodate the rods **2**, **3a** and **4a**, and it also has other apertures **5m** to receive the rods **5a**. A hole **5n** at the lower end of this lever permits the passage of the lowermost one of the rods **6a**. Lever **6c** (Fig. 6) has a larger aperture **6k** to accommodate the rods **2**, **3a**, **4a** and **5a**, and it also has holes **6n** to receive the rods **6a**.

35 The push rods **2f**, **3f**, **4f**, **5f** and **6f** abut respectively at their upper ends (Fig. 2) against hit indicating members or disks **2g**, **3g**, **4g**, **5g** and **6g**, which are normally concealed behind the wall **8**. All the indicators are spaced apart and mounted respectively on a horizontal axle **25** which extends longitudinally of the casing and 40 is mounted on the rear of the front wall of the same. Obviously these indicators may be of different colors or marked in some distinctive way to indicate from a distance whether the bull's-eye or one or the other of the rings were 45 struck by the bullet. From the foregoing it will be understood that if the bull's-eye **1** is struck, its rod **2** will be moved rearwardly and this will cause the abutment **2b** to move the lever **2c** rearwardly. As the arm **2e** of that lever is thus 50 thrown upwardly, it will raise the push rod **2f** and it in turn will throw the corresponding indicator **2g** upwardly.

55 Likewise with any one of the ring sections, if it is struck, its abutment will operate the corresponding lever, which will throw up the proper push rod and move the corresponding disk into indicating position.

60 For the purpose of temporarily holding any one of the indicating discs in raised or indicating position, each indicator has a series of ratchet teeth **26** (Fig. 3) that cooperate with a pawl **27**, normally positioned out of the path of movement of the teeth. The pawl is pivotally mounted on a pin **28** secured to the rear of the front wall **8** of the target and it is controlled in the following way. The rear ends of the guide rods **3a** to **6a** inclusive (Fig. 2), and an abutment **2x** on the rod **2**, are arranged to abut against the board portion **29** of a cushioning lever **30** pivotally mounted at **31** on the internal frame. An arm **32** extends forwardly from this lever and is provided with a cup **33** to receive a ball weight **34**. This weight normally rests in the ring portion 70 **35** (Fig. 13) of a lever **36** pivotally mounted at

its rear end **37** and connected at its forward end **38** to the lower end of a link **39**. The upper end of this link (Fig. 3) is connected to a bell crank lever **40** pivotally mounted at **41** on the rear of the wall **8**. Another link **42** connects the bell crank lever to the pawl **27**, and it will be understood that each time the lever **30** is actuated, the ball weight **34** will be thrown upwardly, and as this relieves the lever **36** of the weight of the ball, a spring **43** connected to the pawl **27** can pull the latter into position to engage the teeth **26** of any one of the indicators. The head **27a** (Fig. 12) of the pawl is elongated for this purpose.

15 The weight ball is arranged to travel in a runway consisting of a vertical chute **34a**, a rearwardly and downwardly inclined portion **34b** and a forwardly and downwardly inclined portion **34c**, and when the ball is thrown upwardly, it will pass over the barrier **34d** within the runway and 20 will then roll first backwardly and then forwardly until it drops into the chute **34a**. When it does this it will engage the lever **36** and as the weight **34** exerts greater force than the spring **43**, the pawl **27** will be swung in a counter-clockwise 25 direction, thereby disengaging the teeth **26** and allowing the indicator which has been temporarily held in raised position to drop back into normal position behind the wall **8**.

30 In order to cushion the movement of the board portion **29** of the lever **30**, this portion is of about the same shape in outline as the interior of a box **44** arranged on the internal wall **21** and consequently a cushion of air will form within the chamber **45**. For further dampening purposes, the box may be mounted on the wall **21** by means of threaded bolts **46** having nuts **47**, which are used to adjust coil springs **48** positioned on the bolts.

35 The various levers heretofore mentioned are 40 preferably provided with springs **49** for returning them to normal position.

45 It will be understood from the above description that immediately after the bull's eye or any one of the rings of the target is struck, the corresponding indicator will be thrown upwardly and at the same time the lever **30** will act to throw the weight ball **34** upwardly to release the pawl **27** so that the spring **43** can swing it in a clockwise direction into engaging position. 50 However, as soon as the ball has traveled through its runway, it will drop on to the lever **36** and this will result in releasing the pawl from the teeth **26** so that the indicator may drop back into the normal position.

55 For the purpose of indicating whether the target has been struck high or at one side or the other, the uppermost guide rods (Fig. 2) of the rings **3**, **4**, **5**, and **6** are provided with abutment 60 collars or elements **3h**, **4h**, **5h** and **6h** respectively, and these rods pass through holes in the upper end portion of a lever **50**, (Fig. 4), which is pivotally mounted on a horizontal pin **51** and has a slot **52** to accommodate the lowermost guide rods 65 of these rings as well as the rod **2**. Should any one of the rings be struck high it will be tilted about the universal joint near the lower end of the same and its uppermost rod in moving axially rearwardly will actuate the lever **50** through the 70 instrumentality of its abutment (**3h**, **4h**, **5h** and **6h**). The lever has a forwardly and laterally extending arm **53** (Fig. 3) which actuates another substantially vertical push rod **54** guided by bearings **55** mounted on the rear of the wall **8**. The 75

push rod actuates an upper high shot indicator 56 that is pivotally mounted at 57 on the rear of the wall 8. A weight arm 58 on this indicator normally holds the same in concealed position 5 and in contact with a stop pin 59.

An abutment collar 60 on the push rod 54 cooperates with one of the bearings 55 and limits upward movement of this push rod.

In operation let us assume for example that 10 the ring 4 is struck high. Its upper portion will move rearwardly and force the rod 4a axially backward. The abutment collar 4h of this rod will move the lever 52 rearwardly and cause its arm 53 to rise and actuate the push rod 54 which 15 in turn will operate the indicator 56.

To take care of shots impinging against one side or the other of the rings, the guide rods 3a, 20 4a, 5a and 6a at the right-hand side of the vertical central plane of the target are also provided with abutments similar to the abutments 3h, 4h, 5h and 6h, and they cooperate with a lever 61 (Fig. 4) having a horizontal series of holes 62 to accommodate these particular guide rods. This lever also has a forwardly and laterally extending arm 63 (Fig. 3) which engages 25 and operates an arm 64 projecting from a normally concealed indicating flag 65 which is pivotally mounted at 66 on the right-hand portion of the rear side of the wall 8. After this flag has 30 been actuated, a spring 67 returns it to normal concealed position.

Another lever 68 (Fig. 4), which is also mounted on the pivot pin 51, is provided with a horizontal series of holes 69 to accommodate the left-hand ones of the guide rods of the rings 3, 4, 5 35 and 6, and these guide rods have abutment collars similar to the collars 3h, 4h, 5h and 6h to actuate the lever 68 when the left side of any one of these rings is struck. This lever also has 40 a forwardly and laterally extending arm 70 (Fig. 3) which cooperates with the arm 71 of a normally concealed left-hand hit indicating flag 72 pivotally mounted at 73 on the rear of the left-hand side of the wall 8, and normally held in concealed position by a spring 74.

From the above description taken in connection with the accompanying drawings, it will be clear that the impact of a bullet on the target causes indication of the particular point of impact. Of course, if either one of the rings is struck low, there will be no actual indication of this by means of flags or the like, but the failure of a flag to appear will serve to inform the marksman that the shot was low.

While I have disclosed what I now consider to be a preferred embodiment of the invention in such manner that the same may be readily understood by those skilled in the art, I am aware that changes may be made in the details disclosed without departing from the spirit of the invention 55 without departing from the spirit of the invention as expressed in the claims.

What I claim and desire to secure by Letters Patent is:

1. In a target, a casing having a front wall, a substantially cone-shaped lead catcher projecting forwardly from the wall and having its base connected to the latter, target sections positioned within the lead catcher, and a substantially cylindrical wild shot catcher ring surrounding said catcher. 5

2. A self-indicating target comprising target 10 sections, guide rods carrying said sections, slideable mounts for said rods, indicating means actuated by said rods, a movable backstop for the rear ends of the rods and an air cushion chamber of which the backstop forms the front wall. 15

3. A self-indicating target comprising a pivotally mounted indicating disc provided with ratchet teeth, a pawl cooperating with the teeth for temporarily holding the disc in indicating position, means for moving the pawl toward said 20 teeth, means for normally holding the pawl in a position out of the path of movement of the teeth, the last mentioned means including a lever and cooperating weighted ball, and means actuated by a shot striking the target for forcing the 25 ball out of contact with the lever to allow the pawl to move into position to engage said teeth.

4. A self indicating target comprising a pivotally mounted indicating disc provided with ratchet teeth, a pawl cooperating with the teeth for temporarily holding the disc in indicating position, means for moving the pawl toward said 30 teeth, means for normally holding the pawl in a position out of the path of movement of the teeth, the last mentioned means including a pivotally mounted lever, a link connected to the free end of said lever and joining the latter to said pawl, said lever being provided with a pocket at its free end, a weighted ball normally resting in 35 said pocket, and means actuated by a shot striking the target for forcing the ball out of said pocket to allow the pawl to move into position to engage said teeth. 40

5. A self indicating target comprising a pivotally mounted indicating disc provided with 45 ratchet teeth, a pawl cooperating with the teeth for temporarily holding the disc in indicating position, means for moving the pawl toward said teeth, means for normally holding the pawl in a position out of the path of movement of the teeth, said last mentioned means including a pivotally mounted lever, a link connected to the free end of said lever and joining the latter to said pawl, said lever being provided with a pocket at its free 50 end, a weighted ball normally resting in said pocket, means actuated by a shot striking the target for forcing the ball out of said pocket to allow the pawl to move into position to engage said teeth, and means for temporarily delaying the return of said ball to said pocket. 55 60

WILLIAM A. WALTHERS.
